UNITED STATES PATENT OFFICE

151,082

DESIGN FOR A FOOD WARMER AND SERVER

Clifford Brooks Stevens, Milwaukee, Wis., as signor to William P. Howlett, Chicago, Ill.

Application September 25, 1946, Serial No. 133,544

Term of patent 7 years

(Cl. D44—1)

To all whom it may concern:

Be it known that I, Clifford Brooks Stevens, a citizen of the United States, residing in Milwaukee, in the county of Milwaukee and State of Wisconsin, have invented a new, original, and ornamental Design for a Food Warmer and Server, of which the following is a specification, reference being had to the accompanying drawing, forming a part thereof.

In the drawing:

4—4 of Figure 1 and looking in the direction of the arrows.

I claim:

The ornamental design for a food warmer and server, substantially as shown.

CLIFFORD BROOKS STEVENS.
